SHAFT-RECIPROCATED DEBARKING TOOL MOUNTED IN SWINGABLE GUIDEWAY

James Navarro Whitaker, Healdsburg, Calif.

Application March 5, 1956, Serial No. 569,318

5 Claims. (Cl. 144—208)

The present invention relates to an improved device for removing bark from logs, and more particularly, aims to provide such a device of simple and rigid construction which, by a simple change of tools, can effectively debark both redwood and fir logs.

With the above and still more particular objects and advantages in view and which will each appear and be understood in the course of the following description and claims, the invention consists in the novel construction and in the adaptation and combination of parts hereinafter described and claimed.

In the accompanying drawings:

Figure 1 is a fragmentary, transverse, vertical sectional view of one of my peeler units equipped with the redwood-debarking tool and in operation on a log and corresponds to the line 1—1 of Fig. 2.

Fig. 2 is a fragmentary front elevation to a reduced scale of a gang of my peeler units operatively mounted on a shaft.

Fig. 3 is a fragmentary front elevation of a guide head and related structure taken similarly as in Fig. 2 with parts broken away and enlarged.

Figs. 4 and 5 are perspective views of the redwood- and fir-debarking tools, respectively.

Referring to the drawings, it is seen that a longitudinal shaft 30 carries a gang of my peeler units. This shaft should be adjustable so that it may be shifted to suit the diameter of the log from which the bark is to be peeled.

Each peeler unit has a pair of parallel spaced arms 17 which are freely journaled at one end on the shaft 30 by bosses 18 so that the shaft can turn with respect to the arms. The other end of the arms has an elbow bridged at the outside by a flange 29 (Fig. 1) and making a rigid connection with a guide head 31. It will be noted that the inside of this elbow is directed toward the log 14 to be peeled. This log may be chucked in any suitable manner for rotation in the direction indicated in Fig. 1 and about a longitudinal axis parallel to the shaft 30.

The guide head 31 has a longitudinal guide slot 16 of rectangular cross section extending therethrough from a bull-nose for selectively receiving peeler tools 15 or 27, the former tool being designed primarily for redwood and the latter being suitable for fir. The tool 15 has a rounded guide nose 15a for engaging the peeled surface of the log and following the contours thereof. As shown in Fig. 1, this serves to position a pointed bark-removing wedge 20 which projects forwardly from the tool 15 and keeps it from digging into the log. The wedge 20 can be produced as an insert piece as shown. The tool 27, on the other hand, has a flat chisel edge 28 and for its intended function does not need a guide nose.

As best shown in Figs. 4-5, the tools 15, 27 each have a pair of apertured forks 33 for pivotally receiving a link 34 at 35. This link is in turn pivotally connected at 36 to a pair of bell cranks 22 which have a pivotal connection by a pin 23 with the arms 17 at their elbow. A rod 25 is located between the arms 17 and makes a

pivotal connection 37 by a necked end with the bell cranks 22. At its other end the rod 25 has a boss which is journaled on a respective eccentric 12 which is fixedly mounted on the shaft 30. It will be apparent from the foregoing that as the shaft 30 is turned the peeling tools 15 or 27 will be responsively reciprocated within their guide heads 31. This reciprocating movement will result in bark-removing forces supplementing the forces otherwise exerted on the bark 26 by the tools due to the turning of the log 14. From Fig. 2 it will be noted that the throws of the eccentrics 12 are staggered circumferentially of the shaft 30 so that the tools of the debarking units will not be acting with full force on the bark at the same time. In this manner the power requirement for shaft 30 is minimized.

It is thought that the invention will have been clearly understood from the foregoing detailed description of my now-preferred embodiments. Changes in the details of construction will suggest themselves and I accordingly intend that no limitations be implied and that the here-to annexed claims be given the broadest interpretation which the employed language fairly permits.

Having thus disclosed my invention what I claim as new is:

25. 1. An improved device for peeling logs comprising, a shaft journal-mounted about an axis of rotation spaced outwardly from and in parallel relation to the longitudinal axis of a log rotatable on its said axis, a bark-removing tool, a guide-head assembly swiveled at one end about said axis of rotation and having its other end slidably receiving said tool with the latter extending endwise beyond said assembly for contacting a log being peeled, and means eccentrically journaled on said shaft and operatively connected with said tool for imparting endwise reciprocating movement to the tool relative to said guide-head assembly.

2. An improved device for peeling logs comprising, a shaft journal-mounted about an axis of rotation spaced outwardly from and in parallel relation to the longitudinal axis of a log rotatable on its said axis, a bark-removing tool, a guide head slidably receiving said tool with the latter extending endwise beyond one end of the guide head for contacting a log being peeled, an arm extending by one of its ends rigidly from the other end of said guide head at an obtuse angle with respect thereto and having its other end swiveled about said axis of rotation, said obtuse angle being directed toward the log, and means eccentrically journaled on said shaft and pivotally operatively connected with said tool for imparting endwise reciprocating movement to the tool relative to said guide head.

3. An improved device for peeling logs comprising, a shaft journal-mounted about an axis of rotation spaced outwardly from and in parallel relation to the longitudinal axis of a log rotatable on its said axis, a bark-removing tool, a guide-head slidably receiving said tool with the latter extending endwise beyond one end of the guide head for contacting a log being peeled, a pair of transversely spaced arms extending by one of their ends rigidly from the other end of said guide head and having their other ends swiveled about said axis of rotation, a rod located between said arms and eccentrically journaled by one end on said shaft, the other end of said rod being operatively interconnected with the other end of said tool for imparting endwise reciprocating movement to the tool relative to said guide head.

4. An improved device for peeling logs comprising, a shaft journal-mounted about an axis of rotation spaced outwardly from and in parallel relation to the longitudinal axis of a log rotatable on its said axis, a bark-removing tool, a guide head slidably receiving said tool with the latter extending endwise beyond one end of the guide head for contacting a log being peeled, a pair of parallel,

spaced elbow arms extending by one of their ends rigidly at an elbow from the other end of said guide head with the inside of such elbow being directed toward such log and having their other ends swiveled about said axis of rotation, a rod located between said arms and eccentrically journaled by one end on said shaft, and a bell crank pivoted to said arms at said elbow and operatively pivotally interconnected to the other end of said rod and to the other end of said tool for imparting endwise reciprocating movement to the tool relative to said guide head.

5. An improved device for peeling logs comprising, a shaft journal-mounted about an axis of rotation spaced outwardly from and in parallel relation to the longitudinal axis of a log rotatable on its said axis, a bark-removing tool, a guide head having an endwise guide slot therethrough slidably receiving said tool with the latter extending endwise by a bark-peeling edge beyond one end of the guide head for contacting a log being peeled, an arm extending rigidly by an elbow at one of its ends from

10

5

the other end of said guide-head with the inside of such elbow being directed toward such log, the other end of said arm being swiveled about said axis of rotation, a bell crank pivotally mounted at said elbow, a rod eccentrically journaled on said shaft and pivotally connected to said bell crank, and a link pivotally interconnecting said bell crank and the other end of said tool, whereby reciprocating endwise movement is imparted to the tool relative to the guide head responsive to turning of the shaft.
